UNITED STATES PATENT OFFICE

2,276,053

ADJUSTABLE RECLINING CHAIR

Hans Luckhardt and Anton Lorenz,
Berlin, GermanyApplication July 24, 1939, Serial No. 286,152
In Germany April 8, 1939

12 Claims. (Cl. 155—106)

Our invention relates to an adjustable reclining chair or the like, and more particularly to an adjustable reclining chair or the like provided with a leg-rest pivoted to the seat and a mechanism for swinging said leg-rest about its pivot point when the back-rest or the seat is moved from one position into another.

In the hitherto known adjustable reclining chairs of above described type, the mechanism for swinging the leg-rest in dependence on the movement of the back-rest or seat is rather complicated and only permits an elevation of the leg-rest into a position inclined to the horizontal at an angle of about 45°. Furthermore, the mechanisms of the hitherto known reclining chairs require a comparatively great reclining movement of the back-rest and the seat for said comparatively small lifting movement of the leg-rest, so that, in the extreme reclining position of the parts of the chair, on the one hand the back-rest and the seat are inclined backwardly to a great extent and on the other hand, the leg-rest is insufficiently lifted, so that the user of the chair cannot rest comfortably.

In our Patent 2,173,283, we describe an adjustable reclining chair, in which, according to a certain embodiment of the chair, the leg-rest may be swung almost into a horizontal plane and almost in line with the seat, when the back-rest is slightly moved into a slightly reclined position. In said reclining chair a back-rest, a seat, a leg-rest, a long connecting link and a short connecting link are pivotally interconnected with each other to form a polygonal structure, one point of said polygonal structure being pivoted to the support of the chair, and cooperating sliding means being arranged on the support and the seat. The mechanism of said reclining chair, however, requires the arrangement of the pivot points of the short connecting link at very advanced points of the chair structure. Moreover, the connecting link-means of said mechanism are arranged above the seat, and it has been found to be impossible to build a similar mechanism solving the same problem but having the connecting link-means below the seat. Furthermore, in many cases it is desirable to provide a reclining chair without a polygonal structure of the above described type, in which, however, the leg-rest may be swung almost in line with the seat, when the seat structure is only slightly moved into a slightly reclined position.

One object of our invention is to provide an adjustable reclining chair or the like, in which the leg-rest pivoted to the seat may be swung

5 almost in line with the seat, when the seat structure is slightly moved from the sitting position into the reclining position, so that, in the reclining position of the parts of the chair, the user of the chair is in a very comfortable relaxed position having his legs supported in an almost horizontal plane and having his body in a slightly reclined position.

Another object of our invention is to provide an adjustable reclining chair, in which the mechanism controlling the swinging movement of the leg-rest from the sitting position into a substantially horizontal position is arranged below the seat.

15 A further object of our invention is to provide an adjustable reclining chair, in which the back-rest is rigidly connected to the seat and the leg-rest may be swung almost in line with the seat by a slight movement of the seat structure comprising the seat and the back-rest.

In order to carry out our invention into practice, we provide an adjustable reclining chair or the like comprising a support, a seat structure, said seat structure being movably mounted on said support, a leg-rest, said leg-rest being pivoted to the seat structure, a link, one end of said link being pivoted to an intermediate point of the leg-rest, and a bell-crank lever having a long arm and a short arm, said bell-crank lever being pivoted to the support, the long arm of said bell-crank lever being pivoted to the other end of said link, and the short arm of said bell-crank lever being operatively connected to an integral portion of said seat structure.

20 30 35 40 45 The above mentioned objects and advantages as well as other objects and advantages will be more fully disclosed in the following specification, reference being had to the accompanying drawing, forming part of this specification in which:

Fig. 1 is a side end view of an adjustable reclining chair, a part of the lower front portion of the support being broken away,

Fig. 2 is a front end view of the chair shown in Fig. 1, a part of the leg-rest and a part of the lower left hand portion of the support being broken away,

Figs. 3, 4 and 5 are fragmentary views of different embodiments of the link and lever mechanism controlling the movement of the leg-rest, partly in section.

Referring now to Figs. 1 and 2, 1 generally indicates a support formed of a continuous rod or the like bent in any suitable shape. The lower portion of the support 1 forms the ground engag-

ing portion 30, the upper portion of the support forms the two arm-rests 32, one on each side of the chair. 2 generally indicates the seat structure comprising the seat 34 and the back-rest 36 immovably connected with each other. The seat structure 2 is pivoted to the support 1 at the point 3 near the ground engaging portion 30 thereof. 4 indicates a leg-rest hinged to the front end of the seat 34 at 5. A supporting means or lug 12 is rigidly secured to the lower front portion of the support 1. 10 generally indicates a bell-crank lever having a long arm 9 and a short arm 11. Said bell-crank lever 10 is pivoted to said supporting means or lug 12 at 13. The end of the long arm 9 of the bell-crank lever is pivoted to one end of a link 6 at 8, the other end of said link 6 is hinged to an intermediate point of the leg-rest 4 at 7. The end of the short arm 11 of the bell-crank lever 10 is pivotally connected with one end of a connecting link 14 at 20, the other end of said connecting link 14 is pivoted to a lug 15 rigidly secured to a lower extension 2a of the seat structure 2. A stop 16 arranged on the lug 12 serves as an abutment for the long arm 9, in order to limit its extreme right hand position (shown in dash lines), when the parts of the chair are in the extreme reclining position. The extreme sitting position of the parts of the chair is limited by stops 19 arranged on the seat 34 and cooperating with the leg-rest 4.

The operation of the reclining chair is as follows:

When the user of the chair swings the seat structure 2 about the pivot point 3 through a small angle α from the sitting position (shown in full lines) into the reclining position (shown in dash lines), the extension 2a, 15 of the seat structure rotates the bell-crank lever 10 about the pivot 13 by means of the connecting link 14, and, in turn, the bell-crank lever swings the leg-rest 4 about the pivot 5 by means of the link 6. The described link and lever mechanism has a great ratio of transmission, so that the leg-rest 4 is rotated about the pivot 5 through an angle of more than 90° and is brought into an approximately horizontal plane almost in line with the seat 34 as shown in dash lines, when the seat structure 2 is slightly rotated about the pivot 3 through the angle α and the seat 34 and back-rest 36 are brought into a slightly reclined position.

The arrangement and the relative proportions of the parts of the link and lever mechanism are such that, in the sitting position, the angle β between the arm 9 and the link 6 is less than 180° , for example about 80° , while, in the reclining position, the angle γ between the arm 9 and the link 6 exceeds 180° , so that the load of the legs resting on the leg-rest 4 in its elevated position (dash lines) cannot cause a turning moment tending to return the parts of the chair from the reclining position into the sitting position. The extreme position of the arm 9 determining the angle γ between the arm 9 and the link 6 is limited by the stop 16, so that the legs resting on the leg-rest 4 are in a stable horizontal position when the user of the chair is in a relaxed position.

If it is desired to return the parts of the chair from the reclining position into the sitting position, small pressure is exerted on the front edge of the seat 34, whereby the extension 2a, 15 forming an integral part of the seat structure 2 is moved downwardly and rotates the bell-crank 70

lever 10 in counter-clockwise direction by means of the link 14. Thus, the long arm 9 of the bell-crank lever returns the leg-rest 4 from its elevated position into the sitting position by means 5 of the link 6, until the leg-rest abuts against the stop 19.

While, according to Figs. 1 and 2, the extension 2a projects from a point of the seat structure 2 near the pivot point 3, the extension could 10 also project from any other point of the seat structure, for example, the extension could be connected to the upper portion of the seat structure, if desired. Moreover, the extension could be entirely omitted without departing from the 15 scope of the invention. If the extension 2a is omitted, the connecting link 14 is enlarged and is pivotally connected with a suitable point of the seat structure 2. Preferably, however, the connecting link 14 is pivoted to a point of the seat structure, which is not too far backward, so that a sufficient rotation of the bell-crank lever 10 may be obtained by a comparatively small rotation of the seat structure 2.

According to the embodiment shown in Fig. 3, 25 a connecting link as indicated by 14 in Fig. 1 is omitted and the short arm 11 of the bell-crank lever is directly connected to the lug 15 of the extension 2a by means of a pivot joint 20. In order to avoid an undesired locking of the mechanism, in which the extension 2a rotates about the pivot 3 and the short arm 11 of the bell-crank lever pivotally connected to the extension 2a rotates about the pin 13 carried by the supporting means 12, the supporting means or link 12 is hinged to the support 1 at 17, so that it may 30 compensate by slight movements about the point 17 the tendency of the ends of the extension and the short arm to depart from each other at the joint 20.

According to the embodiments shown in Figs. 40 4 and 5, the short arm 11 of the bell-crank lever is directly connected to the extension 2a, 15 of the seat structure by means of a pin and slot connection 200, 18, which permits a slight relative movement between the ends of the short arm and the extension during their rotation about the respective pivots 13 and 3, so that, in this instance, the supporting means or lug 12 may be rigidly secured to the support 1. According to 45 Fig. 4, the pin 200 is arranged on the short arm 11 and the lug 15 of the extension 2a is provided with the slot 18 engaging said pin, while according to Fig. 5 the pin 200 is arranged on the lug 15 and the short arm 11 is provided with the slot 18.

While the drawing shows only a single link- 50 and lever mechanism for the movement of the leg-rest in the middle of the chair, two link and lever mechanisms could be arranged, one on each side of the chair, if desired. Moreover, any other mechanism having a great ratio of transmission could be used instead of the mechanism shown in the drawing.

The side portions of the support 1 may be 55 covered with a layer of a suitable covering material, such as fabric, leather or the like, so that the link and lever mechanism arranged below the seat is concealed.

In the embodiment shown in the drawing, the seat structure 2 comprises the seat 34 proper and the back-rest 36 forming an integral piece. If desired, however, the seat structure 2 could consist of several parts; for example, the back-rest could be movably and adjustably connected to 70 75

the seat proper or could be formed of a separate piece rigidly connected to the seat.

While we have shown only a chair, we do not wish that the invention be limited to chairs only. The mechanism for moving the leg-rest may also be arranged in other articles of furniture, such as couches or the like.

We have described preferred embodiments of our invention, but it is clear that numerous changes and omissions may be made without departing from the spirit of our invention.

What we claim is:

1. In an adjustable reclining chair or the like, a support, a seat structure, said seat structure including a seat and a back-rest connected with each other at a fixed angle between the seat and the back-rest, said seat-structure being pivoted to said support, a leg-rest, said leg-rest being pivoted to the seat-structure, a link, one end of said link being pivoted to an intermediate point of said leg-rest, and a bell-crank lever having a long arm and a short arm, said bell-crank lever being pivoted to said support, the long arm of said bell-crank lever being pivoted to the other end of said link, and the short arm of said bell-crank lever being operatively connected to said seat-structure.

2. In an adjustable reclining chair or the like, a support, a seat structure, said seat structure including a seat and a back-rest connected with each other at a fixed angle between the seat and the back-rest, said seat structure being pivoted to said support at a point near the ground engaging portion thereof, a leg-rest, said leg-rest being pivoted to the seat structure, a link, one end of said link being pivoted to an intermediate point of said leg-rest, and a bell-crank lever having a long arm and a short arm, said bell-crank lever being pivoted to said support, the long arm of said bell-crank lever being pivoted to the other end of said link, and the short arm of said bell-crank lever being operatively connected to said seat structure.

3. In an adjustable reclining chair or the like, a support, a seat structure, said seat structure being pivoted to said support, a leg-rest, said leg-rest being pivoted to the seat structure, a link, one end of said link being pivoted to an intermediate point of said leg-rest, and a bell-crank lever having a long arm and a short arm, said bell-crank lever being pivoted to said support, the short arm of said bell-crank lever being operatively connected to an integral portion of said seat structure, the long arm of said bell-crank lever being pivoted to the other end of said link, the angle between said long arm and said link opposite said leg-rest being less than 180° when the parts of the chair are in sitting position and exceeding 180° when the parts of the chair are in reclining position, so that the load resting on the leg-rest is prevented from causing a turning movement tending to return the parts of the chair from the reclining position into the sitting position.

4. An adjustable reclining chair or the like as claimed in claim 3, in which a stop is arranged on the chair structure, which limits the relative position between the long arm of the bell-crank lever and the link in the extreme reclining position of the parts of the chair.

5. An adjustable reclining chair or the like as claimed in claim 3, in which stops are arranged on the chair structure, which limit the relative position between the long arm of the bell-crank lever and the link in the extreme sitting position of the parts of the chair.

6. In an adjustable reclining chair or the like, a support, a seat structure, said seat structure being pivoted to said support, a leg-rest, said leg-rest being pivoted to the seat structure, a link, one end of said link being pivoted to an intermediate point of said leg-rest, a bell-crank lever having a long arm and a short arm, said bell-crank lever being pivoted to said support, the long arm of said bell-crank lever being pivoted to the other end of said link, and a connecting link, one end of said connecting link being pivoted to said short arm of said bell-crank lever, and the other end of said connecting link being pivoted to an integral portion of said seat structure.

7. In an adjustable reclining chair or the like, a support, a seat structure, said seat structure being pivoted to said support, a leg-rest, said leg-rest being pivoted to the seat structure, a link, one end of said link being pivoted to an intermediate point of said leg-rest, and a bell-crank lever having a long arm and a short arm, said bell-crank lever being pivoted to said support, the long arm of said bell-crank lever being pivoted to the other end of said link, and the short arm of said bell-crank lever being connected with said seat structure by means of a pin and slot connection.

8. In an adjustable reclining chair or the like, a support, a seat structure, said seat structure being pivoted to said support, a leg-rest, said leg-rest being pivoted to the seat structure, a supporting link, one end of said supporting link being pivotally mounted on said support, a bell-crank lever having a long arm and a short arm, said bell-crank lever being pivoted to the other end of said supporting link, and a link, one end of said link being pivoted to an intermediate point of said leg-rest, the long arm of said bell-crank lever being pivoted to the other end of said link, and the short arm of said bell-crank lever being pivoted to said seat structure.

9. In an adjustable reclining chair or the like, a support, a seat structure, said seat structure including a seat and a back-rest connected with each other at a fixed angle between the seat and the back-rest, said seat structure being pivoted to said support and being tiltable about its pivot point for a lifting of the front of the seat with respect to the rear of the seat when the seat structure is swung into a reclined position, a leg-rest, said leg-rest being pivoted to the seat structure, a link, one end of said link being pivoted to an intermediate point of said leg-rest, and a bell-crank lever having a long arm and a short arm, said bell-crank lever being pivoted to said support, the long arm of said bell-crank lever being pivoted to the other end of said link, and the short arm of said bell-crank lever being operatively connected to said seat structure.

10. In an adjustable reclining chair or the like, a support, a seat structure, said seat structure including a seat and a back-rest connected with each other at a fixed angle between the seat and the back-rest, said seat structure being pivoted to said support, a portion of said seat structure extending near the ground engaging portion of said support, a leg-rest, said leg-rest being pivoted to the seat structure, a link, one end of said link being pivoted to an intermediate point of said leg-rest, and a bell-crank lever having a long arm and a short arm, said bell-crank lever being pivoted to said support at a point near the ground engaging portion thereof, the long arm of said bell-crank lever being pivoted to the other

end of said link, and the short arm of said bell-crank lever being operatively connected to said portion of said seat structure.

11. In an adjustable reclining chair or the like, a support, a seat structure, said seat structure being pivoted to said support at a point near the ground engaging portion thereof, a portion of said seat structure extending near the ground engaging portion of said support, a leg-rest, said leg-rest being pivoted to the seat structure, a link, one end of said link being pivoted to an intermediate point of said leg-rest, a bell-crank lever having a long arm and a short arm, said bell-crank lever being pivoted to said support at a point near the ground engaging portion thereof, the long arm of said bell-crank lever being pivoted to the other end of said link, and a connecting link, one end of said connecting link being pivoted to said short arm of said bell-crank

lever, and the other end of said connecting link being pivoted to said portion of said seat structure.

12. In an adjustable reclining chair or the like, a support, a seat structure, said seat structure being pivoted to said support, a leg-rest, said leg-rest being pivoted to the seat structure, a link, one end of said link being pivoted to an intermediate point of said leg-rest, and a bell-crank lever having a long arm and a short arm, said bell-crank lever being pivoted to said support, the long arm of said bell-crank lever extending upwardly from its pivot point and being pivoted to the other end of said link, and the short arm of said bell-crank lever being operatively connected to said seat structure.

HANS LUCKHARDT.
ANTON LORENZ.
